United States Patent Office

Des. 231,301

Patented Apr. 16, 1974

231,301

FOOD BOWL

John F. Krieger, Hales Corners, and Robert S. Block,
Bayside, Wis., assignors to Breakthru Incorporated,
Milwaukee, Wis.

Filed Apr. 28, 1971, Ser. No. 138,390

Term of patent 14 years

Int. Cl. D7—01

U.S. Cl. D7—5

FIG. 1.

FIG. 2.

FIG. 3.

FIG. 1 is a side perspective view of a food bowl, showing our new design;

FIG. 2 is a top plan view; and

FIG. 3 is an end elevational view.

The side not shown is plain.

We claim:

The ornamental design for a food bowl, as shown and described.
